UNITED STATES PATENT OFFICE.

JAMES M. MURPHY, OF DORMONT, PENNSYLVANIA.

GAME.

Application filed August 5, 1924. Serial No. 730,186.

To all whom it may concern:

Be it known that I, JAMES M. MURPHY, a citizen of the United States, residing at Dormont, county of Allegheny, and State of Pennsylvania, have invented a new and useful Improvement in Games, of which the following is a full, clear, and exact description.

The present invention relates broadly to games and more particularly to an improved baseball game device.

It has heretofore been proposed in the art to which the present invention relates to provide a game board having the different players for a game of baseball indicated thereon with means for mechanically actuating the pitcher to cause him to throw a ball and means for mechanically actuating the batter in timed relation to cause him to hit the thrown ball. Such structures however have usually required a special manual positioning of the ball for each play. The present invention has for one of its objects a baseball game device embodying a mechanical representation of a pitcher and batter with means whereby the throwing arm of the pitcher is automatically supplied with the previously played ball, so that the ball is ready for re-play.

In the accompanying drawings there are shown for purposes of illustration only certain preferred embodiments of the present invention, it being understood that the drawings do not define the limits of my invention as changes in the construction and operation disclosed therein may be made without departing from the spirit of the invention or the scope of my broader claims.

In the drawings,

Figure 1 is a top plan-view of a game board embodying the present invention;

Figure 2 is a longitudinal sectional view through the board shown in Figure 1, certain of the parts being in elevation;

Figure 3 is a vertical sectional view on an enlarged scale on the line III—III of Figure 1;

Figure 4 is a perspective view of a portion of the actuating mechanism, and

Figure 5 is a detailed sectional view on an enlarged scale illustrating a modified embodiment of the present invention.

In carrying out the present invention there may be provided a board 2 of any desired size having supporting legs 3 and 4, the legs 4 preferably being of slightly

greater height than the legs 3 whereby the board when supported on a horizontal surface will incline slightly forwardly as shown in Figure 2. Above the legs 4 there is provided a hood 5 preferably inclined backwardly and downwardly to deflect a ball projected thereagainst downwardly against the board 2.

Adjacent the end of the board opposite the hood 5 there is provided a batter 6 carrying a horizontally projecting bat 7 normally inclined slightly to the vertical for reasons which will be hereinafter more readily apparent. The amount of inclination is adapted to be varied by loosening an adjusting nut 8 and turning the bat to the desired position.

Intermediate the batter and hood there is provided a pitcher 9 having mounted therein a shaft 10 carrying at one end a gear 11 to which is operatively secured a throwing device 12. This throwing device preferably comprises a hub 13 carrying a throwing arm 14 normally projected outwardly into the position shown in Figure 2 by means of a spring 15, the outer limit of movement of the throwing arm being controlled by a pin 16 extending through the stem 17 projecting rearwardly from the throwing arm. This throwing arm is provided with a ball opening 18 for the reception of a ball 19 illustrated in Figure 2 in full lines as in flight toward the batter and in dotted lines as having been hit in the direction of the hood 5.

For effecting rotation of the gear 11 and the throwing device 12, there is provided a shaft 20 extending longitudinally of the board below the same and journaled at its rear end in a bracket 21. At its front end this shaft passes through one of the supporting legs 3 and is provided with an operating crank 22. At a point intermediate its length the shaft 20 carries either a worm or spiral gear 23 adapted to mesh with the gear 11 whereby rotation of the shaft 20 in the proper direction will be effective for turning the throwing device in a clockwise direction.

Underneath the throwing device and in the path of rotation of the throwing arm is a ball collecting pocket 24. At the commencement of play, a ball is manually dropped into this pocket. Thereafter the shaft 20 is rotated to cause the throwing arm to rotate in a clockwise direction and enter the pocket.

Due to the curvature of the forward end of the throwing arm it permits the nose 25 to pass over the ball thereby causing the ball to enter the ball opening 18. Preferably the 5 pocket 24 is rounded at the bottom so the ball always lies in the center of the pocket where it will always be picked up by the throwing arm. Continued rotation of the throwing device brings the projecting portion 25 of the throwing arm into engagement with the upwardly inclined cam surface 26.

This cam surface gradually approaches the axis of rotation of the throwing device, whereby it is effective upon rotation of such 15 device to force the throwing arm into the hub 13 against the action of the spring 15. As the throwing device assumes a horizontal position the ball is freely supported within the opening 18. As this position is passed, 20 however, the ball tends to roll further into the opening whereby it is firmly supported therein in a manner such that it will be accurately guided upon its projection. Such projection occurs when the throwing arm reaches the position indicated in Figure 2 25 wherein it is shown as having passed the upper end of the cam surface 26. The ball, guided by the sides of the opening 18, passes in a direction indicated by the arrows *a* against the inclined surface of the bat 7, it being projected therefrom in the direction of the arrows *b*. I have found that materially better results are produced if the face of the bat which engages the ball is provided 30 with a covering of resilient material 27, such as rubber.

In order to make the action more realistic I desire to so mount the batter 6 that the bat may be mechanically swung into impact 40 with the ball. This is accomplished by supporting the batter on a pin 28 extending vertically through the board 2 and carrying at its lower end a crank arm 29, as clearly shown in Figure 4. At its outer end this 45 crank arm is provided with an elongated slot 29' through which extends a pin 30 projecting upwardly from a rod 31. The rod 31 is normally urged toward the right, as viewed in Figures 2 and 4, by a compression 50 spring 32, the rod extending at its forward end through one of the legs 3 and at its rear end through the bracket 21. At a suitable point in the rod beneath the throwing device, it is provided with a vertically adjustable pin 33 adapted to extend upwardly into a position to be engaged by a pin 34 projecting laterally from the gear 11. As the gear 11 is rotated in the clockwise direction, the pin 34 is adapted to engage the pin 33 60 to move the rod 31 to the left and thereby swing the crank lever 29 in the direction indicated by the arrow *c* prior to the time that the throwing device moves out of engagement with the cam surface 26. Just about 65 the time such disengagement occurs, the pin

34 will free the pin 33 thereby enabling the spring 32 to return the batter to normal position in time to cause the bat to meet the ball thrown by the pitcher. The exact time of release of the rod 31 may be accurately controlled by threading the pin 33 through the rod so that it projects a greater or less distance thereabove.

A ball which has been thrown and batted 70 engages the hood 5 and is projected downwardly thereby against the upper surface of the board. This causes it to drop into some one of the angularly extending grooves 35 75 all of which terminate in a common groove 36 leading to the pocket 24 beneath the throwing device. Each of the grooves 35 is suitably designated so as to indicate to the players the value of the ball which has been hit. If desired the grooves may be painted in distinctive colors for the convenience of 80 the players. For example the "out" grooves 85 may be painted red and the "base-hit" grooves painted white.

A number of suitable markers 37 is provided which markers are adapted to be 90 moved around the bases in accordance with the value of the ball just played, each base having a suitable opening 38 to receive a projection 39 on the markers. At some suitable point the board is also provided with 95 openings 40 adapted to receive similar markers for indicating the number of men out and with another series of holes 41 adapted to receive such markers to indicate the number 100 of runs made during any inning. At the conclusion of any one inning the total number 105 of runs may be entered in the appropriate square 42 on the board. By reason of the arrangement of the grooves 35 and 36 it will be apparent that the ball automatically returns each time to the pocket 24 from which it is automatically picked up by the operation of the throwing device. This makes it unnecessary to manually position the ball 110 for each play.

In Figure 5 I have indicated a slightly modified form of throwing device in which parts corresponding to parts heretofore described are designated by the same reference characters having a prime affixed thereto.

In this embodiment, the hub 13' carries a double ended throwing arm 14' whereby two balls are thrown for each revolution of the gear 11'.

The advantages of the present invention 120 arise from the provision of a game device adapted to simulate a game of baseball as actually played and so constructed that the ball is automatically delivered to the pitcher after each play.

Further advantages arise by reason of the construction of the board permitting markers to be used to indicate not only the position of the players on the bases but also the 125 number of outs and the number of runs 130

scored up to any time during the inning being played.

I claim:

1. In a game device, a board having a plurality of play grooves therein delivering to a common pocket, a pitcher having a throwing arm movable through said pocket for picking up a ball therein, and a means for projecting said ball from said throwing arm at a predetermined time, substantially as described.

2. In a game device, a board having a plurality of play grooves therein adapted to deliver a ball to a common pocket, a pitcher having a rotating throwing arm movable through said pocket for picking up a ball therein, and means for projecting said ball from said throwing arm at a predetermined time, substantially as described.

3. In a game device, a board having a plurality of play grooves therein delivering to a common pocket, a pitcher having a throwing arm movable through said pocket for picking up a ball therein, means for projecting said ball from said throwing arm at a predetermined time, and a batter in line with the projected ball, substantially as described.

4. In a game device, a board having a plurality of play grooves therein delivering to a common pocket, a pitcher having a throwing arm movable through said pocket for picking up a ball therein, means for projecting said ball from said throwing arm at a predetermined time, a batter in line with the projected ball, said batter having a mechanically actuated bat operated in timed relation to the projection of said ball, substantially as described.

5. In a game device, a board having a plurality of play grooves therein, a hood for deflecting a projected ball downwardly into one of said grooves, all of said grooves adapted to deliver a ball to a common pocket, a pitcher having a throwing arm movable through said pocket for picking up a ball therein, means for projecting a ball from said throwing arm at a predetermined time, and a batter for batting said ball against said hood, substantially as described.

6. In a game device, a board having a plurality of play grooves therein, a hood for deflecting a projected ball downwardly into one of said grooves, all of said grooves adapted to deliver a ball to a common pocket, a pitcher having a throwing arm movable through said pocket for picking up a ball therein, means for projecting a ball

from said throwing arm at a predetermined time, a batter for batting said ball against said hood, and means for operating said throwing arm and said batter in a predetermined time relationship, substantially as described.

7. In a game device, a board having a plurality of play grooves therein, a hood for deflecting a projected ball downwardly into one of said grooves, all of said grooves adapted to deliver a ball to a common pocket, a pitcher having a throwing arm movable through said pocket for picking up a ball therein, means for projecting a ball from said throwing arm at a predetermined time, and a batter for batting said ball against said hood, said batter having a bat inclined downwardly and provided with a resilient batting surface, substantially as described.

8. In a game device, a pitcher comprising a rotating throwing arm, means for moving said arm radially during rotation thereof, said throwing arm having an opening for the reception of a ball, and means for quickly moving said throwing arm in one direction at a predetermined point during the rotation thereof for projecting a ball from said opening, substantially as described.

9. In a game device, a pitcher comprising a rotating throwing arm, means for moving said arm radially during rotation thereof, said throwing arm having an opening for the reception of a ball, means for quickly moving said throwing arm in one direction at a predetermined point during the rotation thereof for projecting a ball from said opening, and a batter having a bat in the path of projection of such ball, substantially as described.

10. In a game device, a pitcher comprising a rotating throwing arm, means for moving said arm radially during rotation thereof, said throwing arm having an opening for the reception of a ball, means for quickly moving said throwing arm in one direction at a predetermined point during the rotation thereof for projecting a ball from said opening, a batter having a bat in the path of projection of such ball, and means for operating said throwing arm and said bat in predetermined time relation whereby the bat is swung to engage the projected ball, substantially as described.

In testimony whereof I have hereunto set my hand.

JAMES M. MURPHY.
